UNITED STATES PATENT OFFICE

97,929

DESIGN FOR AN AUTOMOBILE

Henry J. Edwards, Toledo, Ohio, assignor to The
Willys-Overland Company, Toledo, Ohio, a cor-
poration of Ohio

Application November 10, 1934, Serial No. 53,965

Term of patent 7 years

To all whom it may concern:

Be it known that I, Henry J. Edwards, a sub-
ject of the King of Great Britain, residing in
Ottawa Hills, Toledo, Ohio, have invented a new,
original, and ornamental Design for an Automo-
bile, of which the following is a specification,
reference being had to the accompanying draw-
ings, forming part thereof.

In the drawings, Figure 1 is a side view of the
automobile showing my new design;

Figure 2 is a top view of a portion of the auto-
mobile shown in Figure 1;

Figure 3 is a front view of the automobile shown
in Figure 1.

Figure 4 is a rear elevational view of the auto-
mobile shown in Figure 1.

My design is characterized by the relative
position of the radiator, headlights, hood and
fenders, and the blended curved surfaces of the
headlight cowling.

I claim:

The ornamental design for an automobile, sub-
stantially as shown and described.

In testimony whereof, I affix my signature.

HENRY J. EDWARDS.
